UNITED STATES PATENT OFFICE

LE ROI EARLE HUTCHINGS, OF BUFFALO, NEW YORK, ASSIGNOR, BY MESNE ASSIGNMENTS, TO REMINGTON RAND INC., OF NEW YORK, N. Y., A CORPORATION OF DELAWARE

ARTICULATED INDEX DEVICE

Application filed December 13, 1926. Serial No. 154,418.

This invention relates to articulated index devices and has reference more particularly to index devices of the class described in which a series of card holding members are connected together to form a series and the series is then pasted or otherwise secured to any supporting surface, together with suitable supporting devices for the articulated index members.

In constructing index devices in which a number of card supporting members or pockets are pasted or otherwise secured to a supporting surface, it is often troublesome to so space the card holding members before pasting to the supporting surface, that all will be equally spaced and the overlapping edges exposed on the card are all equal in width. Also no entirely satisfactory supporting means for articulating indexes has been heretofore prepared.

An object of this invention, therefore, is to provide a means for articulating reference bearing members together before attaching by pasting, or by other means, to a supporting surface.

Another object of the invention is to provide a means for supporting the articulated index so that said index will be convenient for ready reference; also to improve articulated indexes in other respects hereinafter specified and claimed.

Reference is to be had to the accompanying drawings, forming a part of this specification, in which

Fig. 1 is an elevation of one of my improved index card holders which is adapted to be connected to other similar holders to form an articulated series of holders,

Fig. 2 is a fragmentary rear elevation of an articulated series of holders,

Fig. 3 is an elevation of a small book in which the articulated holder series of Fig. 2 is secured,

Fig. 4 is a sectional view through the book on the line 4—4 of Fig. 3.

Fig. 5 is a perspective view of a cylinder, to the outer surface of which is pasted or attached the articulated series of holders shown in Fig. 2,

Fig. 6 is a perspective view of an index

frame or device adapted to receive a plurality of the articulated indexes as shown in Fig. 2,

Fig. 7 is a longitudinal sectional view through the index device shown in Fig. 6,

Fig. 8 is a plan view of several of the devices shown in Fig. 6 placed together in abutting position,

Fig. 9 is a plan view of one of the panels forming the device of Fig. 6 with parts broken away to disclose the construction,

Fig. 10 is a transverse sectional view through a portion of the device shown in Fig. 6,

Fig. 11 is a longitudinal, fragmentary, sectional elevation through the device illustrated in Fig. 6, shown in open reference position,

Fig. 12 is a rear elevation of the device shown in Fig. 6, with panels removed.

Figs. 13 and 14 are fragmentary, sectional views taken on the lines 13—13 and 14—14 respectively of Fig. 9,

Fig. 15 is an elevation of a modified form of card holder to be inserted in the panel shown in Fig. 9.

Referring to the drawings in detail, numeral 20 indicates an index holder which is preferably constructed of heavy paper, such as kraft paper.

Along one edge of the holder 20 is attached a sheath 21 of celluloid or other transparent material, said sheath being attached to the holder in any suitable way such as by means of staples or stitches 22. This sheath 21 forms a pocket for the reception of one edge of an insert reference card 23 so that index names or words on the bottom of the insert card 23 are visible through the front wall of the sheath 21. It should be understood that the holder itself may be used for bearing reference data and the sheath 21 may or may not be attached thereto. Also any method of removably attaching the insert card 23 to the holder 20 may be used.

A salient feature of my invention consists in a supporting stub 24 hingedly connected to the holder 20 in any way, such as by a perforated bend line 25. The supporting stub 24 is provided at each outer corner with an outstanding ear 26 adapted to be received in a diagonally extending slot 27 formed in a

similar supporting stub. Thus the tongues 26 are received in the slots 27 and form a means of joining the supporting stubs 24 together to form an articulated series with the sheaths 21 of the index holders lying in overlapping position one on the other and with the width of the overlapping portions of the sheaths all equal. Any other system of articulating means for the stubs 24 such as other systems of interlocking tongues and apertures may be used if desired. The entire structure so far described may be called a "pocket" for the reception of the detachable insert card 23.

15 The rear view of the articulated pocket series is shown in Fig. 2 and it may be seen that an adhesive may now be applied to the exposed portions of the supporting stubs and said articulated series then applied to any 20 supporting surface. The adhesive is then allowed to dry, and the articulated series of pockets will be securely attached to said supporting surface. I do not confine my invention to the use of adhesive in attaching the 25 articulated pocket series to a supporting surface since any other means such as staples or stitches may be used for this purpose and said attaching means may similarly permit the detachment or removal of the articulated pocket 30 series from its supporting surface if so desired.

In Figs. 3 and 4 is shown the articulated pocket series attached to one cover 28 of a small book 29 having an opposite cover 30. 35 When the cover 30 is folded over onto the said articulated pocket series, said series is protected from dust and wear and the book is readily portable. In the form of the device shown in Fig. 5, the articulated pocket series is shown pasted or otherwise attached to the outer surface of a cylinder 31 having a central shaft or hub 32 adapted to be rotatably supported in suitable trunions not shown. This circular device would then be 40 used in a view changing device such as that shown by the patent to Upp, No. 1,090,121, March 10, 1914.

One of the most important frame or supporting devices for the articulated index is 50 shown in Figs. 6-14 inclusive. In this form of the invention, the articulated pocket series is attached, as by pasting, to a cardboard or other suitable material 33, the edges of this cardboard being then inserted under the opposed flanges 34 of a sheet-metal panel 35. One edge of the panel 35 is bent back on itself and secured by means of rivets 36 so as to 55 form a bead 37 having bearing sleeves 38 mounted on each end thereof, such ends protruding beyond the end portion of the panel and said bearing sleeves being secured thereon in any suitable manner. Suitable stop flanges 39 may be formed on the top edge of the body portion of the panel 35 at each 60 extremity thereof (Fig. 9), which cooperate

with a shoulder 40 which is formed on the flanges 34 by forming flattened flanges 41 for a portion of the length of the flanges 34, so as to prevent longitudinal shifting of the cardboard support 33, which is inserted under the flanges 34 between the stop flanges 39 and the shoulder 40 (Fig. 9).

Any suitable frame means may be used for hingedly supporting the panels 35 on the bearings 38, but in the preferred form of the invention this supporting frame is approximately triangular in cross-section as shown in Figs. 6 and 12. Guideways 43 and 44 are formed along an edge on each end 45 of said frame, these slideways being of unequal 80 width and being adapted to hingedly receive the bearings 38. Inside of the wide guideway 43 is a follower member 46 which is adapted to be pressed inwardly by a spring 47, against the ends of the bearings 38. The panels 35 are provided with a cut-out portion 48 which permits the panel bearings adjacent said cut-out portion to be first inserted under the wide slideway 43 against the spring action of follower 46 and then the opposite bearings 38 may be moved into the 90 narrow slideway 44.

Attached to the frame member 42 are two covers 49 and 50, each of which is provided along one edge with a bead 50a, the ends of 95 which are adapted to be received in the ends of guideways 43 and 44. The cover 49 has an offset section 51 which is adapted to receive a flat slide bracket 52 having stop ears 53, formed at one edge thereof. This bracket 52 is adapted to slide freely between the section 51 and the cover 49, its movement in one direction being limited by a pin 54 in said cover 49. When the cover 49 is closed down into approximately horizontal position as shown in Fig. 7 the slide bracket 52 is manually moved toward and in contact with the pin 54. When the cover 49 is lifted to a substantially vertical position, the slide bracket 52 moves downwardly between section 51 and cover 49 under the action of gravity until the lower end rests in a pressed recess 55 formed in one triangular side 56 of the frame member 42. Thus the slide bracket 52 cooperates with the frame 42 in supporting the cover 49 conveniently at a slight angle to the side 56.

When the supporting device is in closed, inoperative position as shown in Fig. 7, the guideways 43 and 44 extend substantially vertically, so that a number of these supporting devices may be placed face to face as shown in Fig. 8. In this face to face position it is convenient to have a label 57 or other identifying means formed on a side of the frame 42 so that the desired index device may be quickly and easily selected. When the cover 49 is raised to a substantially vertical position, the frame 42 moves about the lower hinge bead of the cover 50 under the action 120 125 130

of bracket 52, until one side of the frame 42 rests on the horizontal surface as shown in Fig. 6. In this position the outer edges of the panels 35 become overlapping and visible so that the outer sheaths 21 present to view the index data on the edge of the card inserts 23 thus causing the device to become self-indexing and the desired panel 35 may be selected easily and quickly by reference to these overlapping panel edges.

If desired, holders 58 for articulating card series 59 may be provided in lieu of the pasteboard supporting members 33. These holders 58 have lugs 60 attached to one hinged edge of said holder, said lugs 60 being of approximately the same thickness as the cardboard support 33, are adapted to be inserted under the flanges 34 of panels 35 in edge to edge relation in a common plane to form a support for the attached holders. This form of the invention is shown in Fig. 15 and it should be noted that in this case the articulating card series 59 are removably attached to the panels 35 and also the articulating card series may be removably attached to the holders 58 by providing a transparent sheath 61 along one edge of said holder 58 to receive one end of the articulating card series which at the end opposite the sheath 61 is provided with tongues 62 adapted to be inserted in suitable slots 63 formed in said holder 58.

I would state in conclusion that while the illustrated examples constitute preferred embodiments of my invention, I do not limit myself precisely to the details herein described, since manifestly the same can be considerably varied without departing from the spirit of the invention as defined in the appended claims.

I claim:

1. In an index device, a plurality of pockets each having a hingedly connected stub portion, means for connecting said stub portions together to form an articulated series of pockets having overlapping edges, and a panel adapted to support said series of pockets.

2. In an index device, a pair of covers hingedly connected together, an index card holder having a stub portion hingedly connected thereto, means for connecting a plurality of said stub portions together to form an articulated series of holders having overlapping edges, said stub portions being pasted to one of said covers.

3. In an index device, an index card holder having a transparent sheath attached to one edge thereof, and a stub portion hingedly connected to a second edge of said holder, said stub portion having tongues and apertures formed therein adapted to interlock with other stub portions so as to form an articulated series of stub portions and holders having overlapping edges, said series be-

ing self-supporting without the aid of supplementary articulating means.

4. In an index device, an index card holder, a stub portion hingedly connected to said holder, said stub portion having a tongue and aperture adapted to interlock with other similar stub portions to form an articulated series of stub portions and holders with overlapping edges, and a connecting strip of material pasted to said stub portions.

5. In an index device, an index card holder, a stub portion hingedly connected to said holder, said stub portion having a tongue and aperture adapted to interlock with other similar stub portions to form an articulated series of stub portions and holders with overlapping edges, a connecting strip of material pasted to said stub portions, and a supporting panel adapted to engage said strip of material.

6. In an index device, an index card holder, a stub portion hingedly connected to said holder, said stub portion having a tongue and aperture adapted to interlock with other similar stub portions to form an articulated series of stub portions and holders with overlapping edges, a connecting strip of material pasted to said stub portions, a frame member, and a panel mounted in said frame member for hinging movement and adapted to support said strip of material and holders so that said holders may be rocked about the hinged stub portions and also about the panel hinge.

7. In an index device, a frame member of substantially triangular shape, guideways parallel to one side of said frame member, a plurality of covers hingedly connected to said frame member, panels hingedly connected in said guideways, and a series of articulated index elements secured to each panel.

8. In an index device, a frame member of substantially triangular shape, a plurality of panels hingedly connected to said frame member, each panel bearing a series of overlapping index elements, and a pair of covers hinged to said frame member and normally enclosing said panels, said frame member being adapted to be tilted independently of said covers so that the edges of said panels are moved into overlapping, visible position.

9. In an index device, a frame member, a plurality of guideways on said frame member, a plurality of index panels hingedly connected in said guideways, and a pair of covers hingedly connected to said frame and normally enclosing said panels, one of said covers being adapted to lie flat on a horizontal surface and the other cover being adapted to be raised and thereafter to move the frame member to an inclined position in which the edges of said panels are in overlapping visible position.

10. In an index device, a frame member, a plurality of index panels and covers hinged to said frame member, one of said covers being adapted to lie flat on a horizontal surface, and a bracket slidably mounted on a second of said covers adapted to slide into frame-engaging position to maintain said cover in an open position.
11. In a series of index devices, each device comprising a frame member of triangular shape, a plurality of covers and index panels hingedly connected to said frame member, said frame member being adapted to be inclined relative to said panels and covers so that the edges of said panels are in overlapping position, said index devices being adapted to be superposed with the covers of adjacent devices in face-to-face position, and a label member on the frame member of each index device which is visible when said covers are in face-to-face position.
12. A card holder for visible indexes comprising a sheet formed to provide a holder portion and a stub portion at one marginal edge of the holder portion hingeable relative thereto, a transparent sheath attached to and enclosing another marginal portion of said holder portion, said stub portion having portions of the sheet removed to provide tongues at the free corners thereof, and other portions of said sheet being removed to provide slots for receiving the tongues on an adjacent stub portion.
13. A card holder for visible indexes comprising a sheet formed to provide a holder portion and a stub portion on one marginal edge of the holder portion hingeable relative thereto, means on said holder portion for detachably mounting a record card, said stub portion having portions of the sheet removed to provide tongues at the free corners thereof, and other portions of said sheet being removed to provide parts for receiving the tongues on an adjacent stub portion.
14. In an index device, a plurality of pockets each provided with attaching means for connection to adjacent pockets to provide an interconnected imbricated series, a supporting surface, and means securing each of the connected pockets to the supporting surface.
15. In an index device, a supporting surface and a plurality of pockets each formed for removable attachment to each other to form an imbricated series of interconnected pockets, said series of pockets being mounted on said supporting surface with portions of each pocket adhesively secured thereto.
16. In an index device, a pair of covers connected for hinging movement and a plurality of pockets between said covers, each pocket having a pair of tongues and a pair of slots, the slots of one pocket receiving the tongues of an adjacent pocket to form an imbricated series of pockets, said series being

mounted on one of said covers by securing portions of each pocket thereto.

17. In an index device, a frame member, a plurality of panels mounted for hinging movement on said frame member adjacent one face thereof and extending therefrom, said frame member adapted to be placed on a horizontal supporting surface with said face thereof extending perpendicularly from said surface, whereby said panels are positioned over said surface in superimposed relation, said frame member being formed for movement about one edge on the supporting surface for arranging said face in angular relation thereto, thereby moving the panels to expose the free edges thereof in stepped index relation.
